Inventor,
Henry Redlich

United States Patent Office.

HENRY REDLICH, OF CHICAGO, ILLINOIS.

Letters Patent No. 95,267, dated September 28, 1869; antedated September 22, 1869.

IMPROVED WINDOW.

The Schedule referred to in these Letters Patent and making part of the same.

To all whom it may concern:

Be it known that I, HENRY REDLICH, of Chicago, in the county of Cook, and State of Illinois, have invented an Improvement in "Water-Proofs for Windows;" and I do hereby declare that the following is a full, clear, and exact description thereof, which will enable others skilled in the art to make and use the same, reference being had to the accompanying drawings, making a part of this description, in which—

Figure 1 is an elevation of the jamb-casing of an ordinary window-frame, with the wedge-pieces in position for tightening the sash.

Figure 2, a transverse section of the same, taken on the line *x x*, fig. 1.

Figure 3, a perspective representation of a sash formed to fit the wedge-pieces.

Figure 4, a perspective representation of one of the wedge-pieces removed from the jamb-casing.

Figure 5, a horizontal section of a window-frame, taken above the meeting-rails of the sash, and on the line *z z*, fig. 1.

Figure 6, a perspective representation of the wedge-piece used to tighten the joints of the meeting-rails.

The nature of the present invention consists in the use of wedge-pieces, faced with rubber, or other suitable material, fastened to the jamb-casings, and arranged to fit correspondingly-shaped rabbets in the stiles of the sash, whereby, when the latter are closed, they will be drawn closely to the stops, and thus shut out wind and rain; and further, in a wedge-piece, also faced with rubber, which is arranged to slide between the meeting-rails, and protect this part of the window.

A, figs. 1, 2, and 3, represents the jamb-casing of a window-frame, and

D C B are inside, partition, and outside stops, all of which have the ordinary construction; therefore nothing is claimed in this regard.

E G represent wedge-shaped pieces of wood, which are faced with rubber *ff*, or other suitable material, and fastened to the jamb-casing A, in such positions as to bring one of the rubber facings of each upper wedge against the inside of the outer top B, and one of the

facings of each lower wedge against the edge of the inside stop D, fig. 1.

By this means the upper and lower sash, when they are rabbeted out, as shown at fig. 3, will wedge between the partition-stop C and the wedges E G, and thus not only keep the sash from rattling, but exclude water, and prevent a draught of air through the window.

The devices for closing the joint between the meeting-rails are shown at figs. 5 and 6, and they consist of a wedge-shaped piece, K, which is faced with rubber, or other suitable material, on both of its edges, and operates between a strip of wood, J, projecting upward from the inside of the meeting-rail of the upper sash, and a wedge-shaped strip, L, fastened to the top of the meeting-rail of the lower sash, both strips being made of the same thickness as the sliding wedge shown in perspective at fig. 6.

A lever, *m*, is pivoted to the meeting-rail of the lower sash, near its end, and it has a connecting link or rod fastened to a staple, S, which is driven into the larger end of the wedge-strip K.

This strip is moved longitudinally, by means of the aforesaid lever, to tighten the joint of the meeting-rails, and it is held in place by means of screws V, fig. 5, put through slots made vertically in it, said slots being made long enough to allow the strip K to have a proper movement.

Having thus fully described my invention,

What I claim, and desire to secure by Letters Patent of the United States, is—

1. The combination of the wedge-shaped strips E G, faced with elastic material, stops B C D, and sash H, the latter having grooves I I, corresponding to the form of said strips, as and for the purpose set forth.

2. The combination of the wedge-shaped strip K, strips J L, lever *m*, connecting-rod P, and sash H, as described and shown.
